(57) **CLAIM**

The ornamental design for a diving flashlight, as shown and described.

DESCRIPTION

FIG. 1 is a front elevational view of the diving flashlight showing my new design;
 FIG. 2 is a rear elevational view thereof;
 FIG. 3 is a left side elevational view thereof;
 FIG. 4 is a top plan view thereof;
 FIG. 5 is a bottom plan view thereof;
 FIG. 6 is a front, right perspective view thereof;
 FIG. 7 is a front, left perspective view thereof; and,
 FIG. 8 is a perspective view of the diving flashlight in use. The broken lines in the FIG. 8 depict the environment that forms no part of the claimed design.
